UNITED STATES PATENT OFFICE.

ISAAC VERNON BRUMBAUGH, OF WASHINGTON, DISTRICT OF COLUMBIA, ASSIGNEE
TO AMERICAN STOVE COMPANY, OF ST. LOUIS, MISSOURI, A CORPORATION OF NEW
JERSEY.

STOVE.

Application filed December 27, 1924. Serial No. 758,454.

So-called "grate top" ranges are very difficult to keep clean, owing to the number of seams and joints, the unshielded injecting tubes of the burners, the exposed framework, and the large and clumsy grates. When a material is spilled on a stove or boils over the side of the utensil, it is likely to lodge on the grate, the burner head and injecting tube, the framework, and seep into the seams and joints or fall upon the drip pan below.

Solid top stoves are also open to objection. Grease and some other substances that spill or boil over upon the top of such stoves usually unite with the surface and are removed only with considerable difficulty. In addition the heat radiates from the top, making them undesirable in warm weather or in poorly ventilated kitchens. Moreover, solid top ranges are not as efficient as grate top ranges, owing to the rate at which heat is conducted through a solid top. An object on such a top can be heated only about one-half as fast as on a grate top range.

I have found that the efficiency of even grate top ranges can be increased if a top member whose surface is a reflector of heat is placed near the utensil in a position such that heat waves projected downwardly will be reflected back upon the utensil. If this surface is a good reflector of heat, a person standing near a range equipped with such a device will not suffer from radiant heat. In general a good reflector of heat is a poor absorber of heat. And a good absorber of heat is generally a good radiator of it, and consequently is most undesirable for such top member.

Surfaces that are polished, glossy, bright, burnished, lustrous, shiny, are excellent reflectors of heat. Polished nickel, polished aluminum, enameled metals, etc., are far better heat reflectors, for instance than cast iron or uncoated sheet iron. Surfaces of this character are usually pleasing to the eye, and are easily kept in a sanitary condition.

If a flame comes in contact with a top member that has a reflecting surface, the intense heat is likely to deteriorate the surface or lower its reflecting properties. It is essential therefore to place such a top member in a position relative to the movement of the flame so that heat therefrom will be reflected, but flame contact is unlikely to occur

when the appliance is used under conditions for which it is intended. To best serve these two conditions, an air shield should exist between the member and the flame.

Furthermore in most stoves the entire burner becomes quite hot from radiated, convected and conducted heat. Especially is heating very pronounced when a burner is operated under a solid top. A burner can be adjusted for what is generally considered a good flame and after it has been operated under a solid top for a reasonable length of time, the burner may become so heated that the mixture of air and gas flowing through the burner is in turn heated excessively. This causes such a marked reduction in the rate of injection of air into the burner that the flame may become unsatisfactory for proper combustion of the gas. The gas may not be completely burned. Carbon monoxide may be formed and soot may be deposited on the underneath surface of such a solid top. If, however, a top member is spaced below an article of support, so that heat waves projected toward the mixing chamber, otherwise known as the injecting tube of the burner, are reflected, this difficulty of the reduction of injection of primary air is greatly minimized.

Perhaps the greatest cause of complaint by the public of poor service with cooking appliances results from clogging of the gas orifice. By providing the top member referred to with an upward rib or raised portion around or near each opening in the member as well as around the entire periphery, thus forming a dish-like shape, matter will be retained until removed. A heat reflecting top member to be practical must have strength to resist heat strains therein. It can also be used to partially or entirely support the burners and serve as a base for different forms of supports for utensils. To withstand both heat and weight strains the strength of the top member is increased if edges are turned up or down. Furthermore the strength of the top member can be increased if ribs and other shapes are molded or pressed into it. Such strengthening provisions make it possible to reduce the thickness of the top member and the weight and ultimate cost of the appliance, without reducing its utility for the purpose in view. By the formation of the ribs or raised por-

tions, both of the above objects are accomplished.

In order to maintain the top member at a relatively cool temperature other provisions beside a reflecting surface are highly desirable. Hot gases rise owing to their density. In their movement there is set up a motion of the surrounding atmosphere. An opening through the top member provides not only for means to assemble the burner but also for a movement of air upward. This serves a number of purposes, such as supplying oxygen of the air required for combustion to the flame, air under the top member that may have become heated above the normal room temperature is drawn upward and replaced by cooler air which reduces the temperature of the top member; the temperature of the top member is furthermore reduced by maintaining a constantly moving air space between the top member and the flame, replacement air being drawn from below the surface of the top member.

The top member can be made of any reasonable size and shape. It can be made larger in any direction than the area represented by the usual grate or combination of grates. An extension can be made and used as a supplemental shelf or place to put utensils and other objects while cooking is in progress. The extension can be used as a drain table or for various other purposes. The removable grates can also be placed aside and the area suitable for such purposes greatly increased. There are numerous other purposes for which this top member with its raised or beaded edges can be used. It may be employed, for example, for mixing dough.

An appliance constructed as herein described, presents still greater neatness and a more cheerful appearance when the grates are removed and the portion of the burner that is exposed is neatly covered. Covers can therefore be made to conceal the openings in the top member and also cover the exposed portions of the burners. The outer surfaces of the covers can be made with the same finish as the top member or some other having an attractive or sanitary appearance so as to harmonize with the surface of the top member.

The top member may be utilized as a means of support for burners. Framework for support of burners which usually becomes filthy owing to the difficulty of cleaning can thus be eliminated. Such means of support may be located below or above the surface of the top member or the burner or means of support may rest on the upper surface of the member.

It is essential that the center of the burner head be spaced approximately in the center of the opening in the top member. The form of support for the burner may provide that

when the burner is in proper position, it is held firmly in place; or a simple means of proper spacing of the burner relative to the opening in the top member can be accomplished by joining to or uniting with the burner or top member one or more parts for a spacing purpose.

There are also a variety of ways the utensil may be supported satisfactorily. A simple manner is to extend downward a series of legs or spacers from the article or grate whose upper surface serves as a base or support for utensils. The ends of these legs or spacers may rest on the top member. There should be some provision to hold or guide the grate in place; this can be accomplished by extending arms with turned-down ends into notches or depressions in the top member. The lower ends of the legs or spacers can also be fitted into openings in the top member and serve the double purpose of means of support and a guide for a grate or other supporting device. It is of course also practical to support the grate or article of support for utensils by framework or some other part of the appliance without utilizing the top member in any manner.

There are also a number of satisfactory designs of burners which can be used in combination with the top member. The burner head can be made in various shapes. It is preferable to have the parts of the burner near or slightly above the level or surface of the top member. The opening in the top member can thus be made smaller and the possibility of damaging the top member by the flame or the intense heat is quite remote.

Just as the top member is designed with cleanly features, so grates and gas burners should have cleanly features. A grate or article of support for a utensil is much more easily cleaned if it is not large and clumsy. A grate with smooth rods and bars is much easier to clean than a rough and irregular surface. The ports of burners clog readily if provision is not made to conduct away from the port matter that may lodge on or near the port. A slope downward from the ports will accomplish this purpose.

To secure the foregoing desirable effects and conditions is the object of the present invention, and in the accompanying drawings are shown illustrative embodiments of the invention.

In the said drawings:

Figure 1 is a plan view of a burner or stove embodying the present invention,

Figure 2 is a sectional view on the line 2—2 of Figure 1,

Figure 3 is a detail sectional view on the line 3—3 of Figure 1,

Figure 4 is a plan view of a stove equipped with four burners and showing the extension,

Figure 5 is a detail sectional view illus-

trating a cover in place over the burner opening,

Figure 6 is a vertical sectional view of a modified form of construction,

5 Figure 7 is a plan view of the same,

Figure 8 is a detail vertical sectional view of a modified form of burner head,

Figure 9 is a plan view of the same,

10 Figure 10 is a plan view of a stove equipped with burners of the type illustrated in Figures 6 and 7,

Figure 11 is a detail sectional view showing a modified means for holding a grate in place,

15 Figure 12 is a still different embodiment of the means for holding and positioning the grate.

In the embodiment illustrated in Figures 1-3 inclusive the reflecting member or top member is illustrated as consisting of a single metal sheet 12 having a coating 13 on its upper surface, this coating being of a polished, glossy or bright character, and preferably, though not necessarily white.

20 It may, for example, be of suitable enamel. The member 12-13 is made sufficiently strong and rigid by any suitable means, and is provided with one or more burner openings 14. Its margins are preferably down-turned, as illustrated at 15, and an upstanding rib may be produced at the edges. Around the burner openings 14 a rib 17 may also be formed.

The burner illustrated consists of a head 35 composed of radial arms 18 supporting a vertical neck 19, to the lower end of which is connected the usual injecting tube 20. As shown the head is of greater diameter than the opening 14 and the arms 18 have on their 40 terminal portions depending spaced lugs 21 that embrace the rib 17. The burner is thus properly positioned and the head, it will be noted, in this instance is slightly above the member 12-13. The flame orifice or ports 45 are formed in the arms, as shown at 22, said arms being hollow and in communication with the interior of the neck 19 and injection tube 20.

An article of support in the form of a 50 grate is illustrated, comprising an angular frame 23 having inset supporting fingers 24. This frame is carried on legs 25 that rest upon the member 12-13. In order to position the grate, inwardly extending arms 26 55 are carried by opposite sides of the frame 23 and have downturned terminals 27 at their inner ends, which terminals engage in notches 28 formed in the wall of the opening 14.

60 With this construction, it will be apparent that the flame from the burner is above the member 12-13 and beneath a utensil placed upon the article of support or grate. The upper surface of the member 12-13 causes 65 this member to act as a reflector and thus

reflect the heat rays upwardly, adding to the heat that is delivered directly to the utensil by the flame.

In Figures 6 and 7 a slightly modified form of construction is disclosed. The top 70 member is designated 12^a-13^a and may be of the same character as that above described. The different portions of the grate are given corresponding numerals, but with the exponent —a—. The burner in this instance is of a different type. It consists of an upstanding head 18^a having a central open-ended air tube 19^a therethrough and carried by an injection tube 20^a. An annular outlet slot or orifice between the upper 75 end of the head 18^a and tube 19^a is shown at 22^a, the upper end of the tube 19^a being flared and overhanging said orifice to guide away matter and shield the orifice from falling matter respectively. The head is properly spaced within the opening 14^a of the top member 12^a-13^a by lugs 21^a carried by the head and located in the said opening. The burner is supported from below in this instance by one or more brackets, one of 80 which is illustrated and designated 21^b, the brackets depending from the member 12^a-13^a and constituting support for the burner. The burner may assume various 85 other forms. For instance, in Figure 8, a vertical tubular head is shown at 18^b, and a stem 19^b, extending upwardly within the same, carries a flared cap 20^b, for the same purpose as described, and forming an annular slot or orifice 22^b for the escape of the 90 fuel for combustion.

In Figure 11 is illustrated a different means for positioning the grate. In this modification the member is designated 12^b-13^b, and has upstanding socket elements 28^b, 105 into which the lower ends of the supporting legs 25^b of the grate 23^b are inserted. This obviously operates the same as the arms 26, with their terminals 27 engaging in the notches 28 as above described.

In Figure 12 there is disclosed a modified means for holding the grate in position and may be employed as a substitute for the parts 26-27 and 28 of Figures 1 and 3. In 110 this modified structure the grate has one or more down-turned legs 25^c that engages in a socket 28^c formed with elevated walls.

As shown in Figure 4 a stove may be employed with a plurality of burners and grates, and the top member 12-13 may be 115 extended to form a shelf as 29 that may be used for various purposes. As shown in Figure 10 this extension, therein designated 29^a, may be in the form of a detachable shelf if desired, and as the grates are easily removed, when removed, the openings 14^a may be covered with detachable caps as 30 shown in Figure 5.

120 From the foregoing, it is thought that the construction, operation and many ad-

vantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim, is:

- 10 1. An improved stove and burner therefor, the stove comprising a horizontal top plate having a burner opening, a burner passing through the said opening and located wholly above the top plate, and a grate supported above the said burner, whereby heat is reflected from the top plate upward
- 15

against a utensil placed on the grate, for the purpose specified.

2. An improved stove and burner therefor, the stove comprising a horizontal top 20 plate having its upper surface enameled and a burner manifold opening, a burner connected with the manifold below the top plate, the burner located above the top plate, the top plate having the periphery of the said 25 opening bulged upward for the purpose specified, and a grate supported above the burner whereby a utensil on the said grate receives reflected heat from the burner.

In testimony whereof, I affix my signature.

ISAAC VERNON BRUMBAUGH.
